UNITED STATES PATENT OFFICE.

ALONZO C. RAND AND WILLIAM M. SLOANE, OF NEW YORK, N. Y.

IMPROVED APPARATUS FOR TREATING PETROLEUM SO AS TO PRODUCE OIL AND GAS THEREFROM.

Specification forming part of Letters Patent No. **87,199**, dated February 23, 1869.

To all whom it may concern:

Be it known that we, ALONZO C. RAND and WILLIAM M. SLOANE, both of New York, in the county of New York and State of New York, have invented a new and Improved Process and Apparatus for Generating Gas and Manufacturing "Distillate or Illuminating-Oil from Petroleum;" and we do hereby declare that the following is a full and exact description thereof, reference being had to the accompanying drawings, and to the letters of reference marked thereon, making a part of this specification.

Figure 1 is a vertical section and elevation of our improved apparatus. Fig. 2 is a transverse section of the series of retorts. Fig. 3 is a plan view thereof.

Like letters indicate corresponding parts in all of the figures.

The object of our invention is an apparatus for the manufacture of illuminating-gas and distillate or refined oil from petroleum by the same operation or process, or either separately, if required, and to effect the saving of the permanent gas produced while distilling refined or illuminating oil from petroleum; and it consists in the following process and apparatus for carrying it into operation: first, of a boiler in which the petroleum or other hydrocarbon is first volatilized by distillation; and, second, of a retort or series of retorts in combination therewith, in which said vapor is subjected to a high heat to convert it into a fixed gas; and, third, in the combination with these of a condenser and a series of pipes and stop-cocks, as hereinafter described, for adapting the apparatus to the double use before mentioned.

Petroleum or any residuum thereof, or impure hydrocarbon oil, is first placed in the boiler A, where it is volatilized by the heat of the furnace B, and the vapors pass through the bent pipe K into the retort or series of retorts C, where they are superheated and converted into a fixed gas. From the retort the gas is led through a pipe, d, to a coil, f, in the cooler or condenser E, where it is conducted to the gasometer by the pipe g. Connected with the latter is a goose-neck return-pipe, h,

the bend of which is placed below the coil f, so that any heavy liquid condensed from the gas will, after filling the inverted bend, so as to prevent the passage of gas from the pipe g or vapor from the boiler A, flow back by gravity into the boiler and be redistilled into vapor, which again passes to the retorts.

By this device all condensable liquid from the gas which leaves the retorts is again subjected to the treatment, and this may be repeated until all portions that are convertible into a fixed gas are thus utilized for that purpose.

By first subjecting the material to a moderate heat those portions only are thrown into the retort which are capable of forming gas, and by this means the retort is prevented from becoming obstructed, and its capacity limited by the formation of coke, which, being a non-conductor, so seriously reduces its heating capacity that its frequent removal at great trouble and expense becomes necessary.

By the use of a separate vaporizing-boiler the first may be graduated by increasing, as the evaporation progresses, from a comparatively low temperature when the charge is fresh or the oil of a light grade to as high a heat as may be required to vaporize the denser liquid.

When the commercial value of refined petroleum is such as to make it an object to not use it as a material for making gas, the vapor from the charge in the boiler A is allowed to enter the retort until the spirit of oil, the gasoline, and naphtha are driven off, when the stop-cocks l and m in pipes k and d are closed and the distillate passes through the branch pipe o directly to the condenser, and is drawn off by the branch pipe p. When so employed the fire is withdrawn from the retorts, and the permanent gas which is formed with the distillate rises through the pipe g and is conveyed to the gas-holder. When not desirable to save the distillate, the volatilization of the charge in the boiler is continued until the distillate, paraffine-oil, and most of the residuum are carried into the retorts, the temperature being elevated as the process continues till the volatilization is completed.

If desirable to draw off the heavier oil before the formation of coke in the boiler, it may be done by means of the stop-cock *g*.

A man-hole is provided at *r* for entrance to the boiler when required.

Being thus easily convertible to a double purpose, our apparatus forms a very useful, portable, or fixed apparatus in many situations where both the distillation of oil and the manufacture of gas may be advantageously carried on separately or together.

We do not claim the combination of the petroleum-still for vaporizing with a decomposing retort or retorts; but

What we claim as our invention, and desire to secure by Letters Patent, is—

1. The combination of a vaporizing-boiler,

A, retort C, and condenser E, with their connecting-pipes, when so constructed as to be used either for a gas-generator or for producing distillate of petroleum or for both purposes at the same time, substantially as set forth.

2. In combination with the condenser E and boiler A, the goose-neck return-pipe *h*, for the purpose specified.

In witness whereof we have hereunto signed our names in the presence of two subscribing witnesses.

ALONZO C. RAND.
WM. M. SLOANE.
